UNITED STATES PATENT OFFICE

JAY G. SPARKS, OF CLINCHCO, VIRGINIA, ASSIGNOR OF ONE-FIFTH TO M. CHILDRESS, ONE-FIFTH TO H. J. CHILDRESS, ONE FIFTH TO A. W. MARTIN, AND ONE-FIFTH TO B. P. GOAD, ALL OF CLINCHCO, VIRGINIA

MINER'S PICK

Application filed May 13, 1927. Serial No. 191,198.

This invention relates to picks and more particularly to a pick intended for use by coal miners although it may be used by other workmen.

5 When a miner is digging coal, the pick often digs deeply into the coal and the handle close to the pick head will strike the coal or rock. This causes the handle to be worn away close to the pick head and weakens the handle to such an extent that it must be discarded and a new one substituted.

10 Therefore, one object of the invention is to provide the pick handle with a guard constituting a shield for the portion of the handle close to the head and preventing the handle from being quickly worn away and weakened.

15 It has also been found that, when a miner attempts to pry loosened coal from the main body in the mine, the handle will often be broken off close to the head or wrenched loose so that the head does not fit tightly upon the handle.

20 Therefore, another object of the invention is to provide an attachment which will serve not only as a shield for the handle but also constitute a reinforcement for the handle and securely hold the pick upon the handle.

25 The invention is illustrated in the accompanying drawing, wherein

30 Figure 1 is a view showing the improved pick principally in side elevation and partially in section;

35 Fig. 2 is a transverse sectional view taken on the line 2-2 of Fig. 1;

40 Fig. 3 is a transverse sectional view taken on the line 3-3 of Fig. 1, and

45 Fig. 4 is a perspective view of the combined handle guard and head fastener.

50 The head 1 of the pick is formed with the usual eye 2 through which the handle 3 is passed with its enlarged end portion fitting tightly in the eye and at opposite ends of the eye the pick head is formed with longitudinally extending recesses 4 constituting seats. It should also be noted that opposite side edge portions of the enlarged end of the handle are formed with longitudinally extending grooves 5 which communicate with the recesses 4. Except for the grooves 5 and re-

cesses 4, the pick handle and head are of a conventional construction.

55 In order to reinforce the handle adjacent the head and securely hold the head upon the handle, there has been provided a combined handle guard and head fastener, a perspective view of which is shown in Fig. 4. This combined handle guard and head fastener is formed with a sleeve 6 which fits snugly about the inner end of the enlarged end portion of the handle 3. It should be noted that the sleeve and the enlarged portion of the handle about which it is disposed taper inwardly so that the sleeve cannot be moved toward the outer end of the handle beyond the position shown in Fig. 1. Arms 7 extend from the sleeve 6 toward the outer end of the handle and terminate in stems 8 which are solid, as shown in Figs. 2 and 4, and preferably circular in cross section so that they 60 may fit snugly in the grooves 5 and end portions of the eye 2. The arms 7 are U-shaped in cross section thereby providing side walls 9 which overlie opposed faces of the handle, as shown in Figs. 1 and 3. By referring to 65 these figures, it will be seen that the enlarged portion of the handle close to the pick head will be to a large extent enclosed in metal and, therefore, when the pick is in use, coal or rock will be prevented from wearing the 70 handle away close to the pick head and causing it to be weakened.

75 When the pick is assembled, the handle is first passed through the eye 2 and the head moved to the position shown in Fig. 1 where 80 it will be wedged tightly upon the enlarged end portion of the handle. After the pick head is in place upon the handle the combined guard and head fastener is moved longitudinally upon the handle until it assumes the position shown in Fig. 1 with the stems extending through the end portions of the eye and their free ends projecting outwardly therefrom. The projecting end portions of the stems are then bent over and struck with a hammer or the like until they are seated in the recesses 4. It will thus be 85 seen that the attachment will serve as a shield or guard for the portion of the handle close to the head and also constitute a fastener to 90 95 100 105

securely hold the pick head in place upon the handle and prevent the handle from being wrenched loose or broken when attempting to pry coal or rock loose. When it is necessary to replace a worn out pick or broken handle, the bent end portions of the prongs are straightened and the pick head and handle can be separated.

Having thus described the invention, I claim:

The combination with a pick having the usual handle-receiving eye, and provided at opposite ends of the eye and adjacent the face of the pick with lateral recesses, and a handle having the accustomed enlarged end to obtain a wedging fit in the eye of the pick, and having grooves in opposite edges of the enlarged end, of a combined guard for the handle and fastener for the pick including a sleeve engaging the inner portion of the handle enlargement, arms projecting from the sleeve and extending along the edges and adjacent side portions of the handle enlargement, and stems uniform throughout their length and snugly fitting within the ends of the eye and the grooved edges of the handle enlargement and having their terminal portions seated within the recesses of the eye.

In testimony whereof I affix my signature.
[L. S.] JAY G. SPARKS.
